Primary Examiner — T. Chase Nelson(74) *Attorney, Agent, or Firm* — Banner & Witcoff, Ltd.(57) **CLAIM**

The ornamental design for a shoe outsole, as shown and described.

DESCRIPTION

FIG. 1 is a front perspective view of a shoe outsole showing my new design;

FIG. 2 is a bottom view thereof;

FIG. 3 is a rear perspective view thereof;

FIG. 4 is an enlarged view of an area containing the claimed region in FIG. 1, shown in isolation;

FIG. 5 is an enlarged view of an area containing the claimed region in FIG. 2, shown in isolation; and,

FIG. 6 is an enlarged view of an area containing the claimed region in FIG. 3, shown in isolation.

The broken lines immediately adjacent to the shaded area represent unclaimed boundaries of the design. The broken lines showing the remainder of the shoe are for environmental purposes only and form no part of the claimed design.
